UNITED STATES PATENT OFFICE.

FRANCESCO GENOVESE, OF NEW YORK, N. Y.

MACARONI-PRESS.

1,280,438.

Specification of Letters Patent.

Patented Oct. 1, 1918.

Application filed January 5, 1918. Serial No. 210,537.

To all whom it may concern:

Be it known that I, FRANCESCO GENOVESE, a citizen of the United States of America, residing at New York city, county and State 5 of New York, have invented a new and useful Macaroni-Press, of which the following is a specification.

My invention relates to presses for macaroni and materials of a like manner.

10 Special objects of the invention are to provide improved mechanism for automatically stopping the plunger of the press at the ends of its stroke, and to provide simplified and improved quick-return mechanism for rapidly feeding the plunger.

The invention accordingly comprises automatic stop mechanism for limiting the movements of the plunger consisting of power shut-off devices, and latches controlling the 20 same and disposed in position to be actuated by the plunger, and combined power feeding and quick-return mechanism consisting of a drive shaft geared to the plunger and having both a relatively slow worm gear drive 25 for the power movement, and a relatively fast drive for the quick-return movement.

Other features and details of the invention will appear as the specification proceeds.

30 The accompanying drawings illustrate the invention embodied in a practical commercial form, but I will have it understood that changes and modifications may be made without departure from the true spirit and 35 scope of the invention.

In these drawings:

Figure 1 is a vertical sectional view of the machine taken substantially on the plane of the line 1—1 of Fig. 2.

40 Fig. 2 is a sectional plan view of the machine taken substantially on the line 2—2 of Fig. 1.

Fig. 3 is a broken rear view of the machine.

45 Fig. 4 is a fragmentary detail view of the latch for holding the clutch lever in the clutch-engaged position.

The machine illustrated comprises in general a die 5 having a plunger 6 coöperating 50 therewith and operated by a screw 7 working in a nut block 8 forming a part of the frame 13 of the machine.

The plunger screw is driven by a relatively large gear 9 having a driving hub or 55 sleeve 10 longitudinally slotted at 11 to receive a transverse key 12 projecting from the screw shaft 7. This construction pro-

vides a sliding driving connection between the gear and screw shaft allowing for the longitudinal feeding movement of the screw. 60

The gear 9 is shown as of the internal drive type and is operated by a pinion 14 engaged therewith and mounted on the upper end of an upright drive shaft 15. During the downward or power stroke of 65 the screw operated plunger, this upright drive shaft is driven at a relatively slow rate of speed by means here comprising a worm gear 16 on said shaft, and a worm 17 on an adjoining power shaft 18. Power is 70 applied to this shaft as by means of the belt 19, said belt being shiftable into engagement with either the fast or the loose pulleys 20 or 21 for controlling the application of such power. 75

During the slow feeding movement, the worm gear is clutched to the drive shaft 15 by means, consisting in the present disclosure, of a clutch member 22 slidably keyed on the drive shaft as indicated at 23, and 80 provided on its upper end with clutch jaws 24 for engagement with corresponding clutch jaws 25 on the lower face of the worm gear. This movable clutch element is shifted into engagement with the worm gear clutch 85 element by a shifting lever 26 pivotally supported on the frame at 27 and extending forwardly within easy reach of the operator of the machine.

90 Preferably, means are provided for latching the clutch lever in the clutching position, such means being illustrated as a latch member 28 pivoted on the lever and adapted to be swung up into engagement with a portion of the frame as illustrated in Fig. 4, 95 so as to thereby lock the lever in its shifted position.

At the end of its down stroke the plunger is automatically stopped by means comprising a trip lever 29 pivotally supported at 30 having an annular portion 31 surrounding the gear sleeve 10 in position to be engaged and depressed by the transverse key 12, and connected at its opposite end with a spring 32 pressed latch member 33 which holds the 100 105 spring actuated belt shifting slide 34 in the position to which it is shifted by the handle 35.

In starting the machine the power controlling lever 35 is operated to shift the 110 slide 34 against the tension of its spring 36, said slide carrying a belt guide 37 encircling the drive belt 19. The belt is thereby shifted from the loose on to the tight pulley,

and as this is accomplished, the spring pressed latch drops into an opening or keeper 38 provided for it in the slide. Power is then continuously applied until the 5 plunger reaches the limit of its downward stroke whereupon the latch is automatically retracted in the manner above described and the spring 36 operates the belt shifter to carry the belt back on to the loose pulley.

10 A quick-return feed is provided for the plunger in the form of a quick-return power shaft 39 connected with the upright drive shaft 15 as by means of bevel gears 40 and 41, and provision is made for quick-feeding 15 of the plunger in both directions by providing reversely operating drive belts 42 and 43 for operating this power shaft, said belts normally traveling over the loose pulleys 44 and 45, and arranged to be shifted by a 20 suitable belt shift onto the intermediate fast pulley 46. This belt shift is shown as a slide 47 carrying guides 48 for the respective belts, said slide being acted upon by a spring 49 to return it to the intermediate 25 position indicated in Fig. 3. This belt shifting slide is retained in the position to which it is shifted by a spring pressed latch 50, and this latch is automatically released at the end of the upward feeding movement of the 30 plunger by means of a pivoted trip lever 51 disposed in the path of the plunger and connected with the latch at 52.

The quick-return movement of the plunger is effected by shifting the belt guiding 35 slide in the proper direction to carry the downward feeding belt from its loose pulley on to the intermediate fast pulley. The clutch 24-25 is uncoupled at this time so that the worm gear is inoperative. The 40 gearing 40-41 is so proportioned and the shaft 39 is rotated at such speed that the drive shaft will be rotated at a relatively rapid rate producing thereby a relatively quick-return of the screw operated plunger.

45 As the plunger nears the limit of its upward stroke it contacts with the trip lever 51 which releases the latch 50, permitting the spring operated slide to shift the belts 42 and 43 back again on to their loose pulleys. If

50 a rapid downward or feeding movement of the plunger is desired, the belt shifting slide is merely forced in the opposite direction from that previously described, to carry the reversely running belt on to the fast pulley 55 46. The plunger may then be fed as far as desired, the feeding movement being stopped by releasing the latch 50 and permitting the spring operated belt shift to again carry the belts into the neutral position. This latch

60 50 may be automatically released at the end of the downward feeding stroke of the plunger as by providing a connection 53 from the trip annulus 31, overstanding the

upper end of the rod 54, which carries the latch 50. The downward feeding movement 65 of the plunger may thus be utilized to operate both the trip for the slow power feed and the trip for the relatively quick feed.

By my invention the feeding of the plunger in both directions is automatically limited 70 regardless of whether the machine is being operated by the slow power feed or the quick-return feed. The quick-return feed mechanism may be utilized to feed the plunger in both directions and is readily controlled 75 for such purposes. The slow power feed mechanism is easily controlled and may be locked in the operative position, and both the slow feed and the quick feed mechanisms are of simple construction and operate 80 quietly and efficiently.

I claim:

1. In combination with a screw operated plunger, a gear connected with said plunger, a drive shaft disposed in parallel relation to the plunger, a pinion on one end of said drive shaft engaged with the gear of the screw plunger, a gear on the opposite end of the drive shaft, a quick return shaft and a gear on said quick return shaft in constant engagement with said last mentioned gear on the drive shaft, means for controlling operation of said quick return shaft, a slow feed shaft, a worm on said slow feed shaft, a worm gear loosely mounted on the drive shaft intermediate the ends thereof and engaged by said worm, and means for coupling said worm gear to the drive shaft. 90

2. In combination with a screw plunger, a drive gear provided with a sleeve surrounding the end of said screw plunger and having a longitudinal slot therein, a transverse key upon the screw plunger extending through said slot in the sleeve, power operated mechanism for rotating the gear, a throw-off device for rendering said power mechanism inactive, and tripping means for said throw-off device having an annular portion about the sleeve in position to be engaged by the transverse key aforesaid. 110

3. In combination, a screw plunger, a gear provided with a sleeve surrounding the end of the screw plunger, said sleeve having a longitudinal slot therein, a transverse key upon the screw plunger extending through said slot in the sleeve, power operated mechanism for rotating the gear, a spring operated throw-off device for rendering the power mechanism inactive, a spring latch for holding said throw-off device inoperative, and a pivoted trip lever connected with said latch and having an annular portion surrounding the sleeve in position to be engaged by the transverse key aforesaid. 115 120

FRANCESCO GENOVESE.
